(57) **CLAIM**

The ornamental design for an interactive feline toy, as shown and described.

DESCRIPTION

FIG. 1 is a front and bottom isometric view of the interactive feline toy showing my new design;

FIG. 2 is a rear and top isometric view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top view thereof the toy; and,

FIG. 8 is a bottom view thereof the toy.

The broken lines are for illustration only and form no part of the claimed design.
